SWASH PLATE PUMP ADJUSTING MEANS

John Thomas Gondek, Minneapolis, Minn., assignor to Northern Pump Company, Minneapolis, Minn., a corporation of Minnesota

Application March 24, 1942, Serial No. 436,025

3 Claims. (Cl. 74—60)

This invention relates to a pump and particularly to a pump of the swash plate type. Such pumps have a tilting plate in which the swash plate is rotatable and the said tilting plate is swingable about an axis and movable to different positions to vary the stroke of said pump.

It is an object of this invention to provide a novel, simple and efficient means for swinging the tilting plate to vary the stroke of the pump.

It is a further object of the invention to provide a novel, simple and efficient means for swinging said tilting plate, which means is quite rugged and includes a member rigidly secured to said tilting plate having a head projecting therefrom, means embracing said head and a member movable at right angles to the axis about which the tilting plate swings in which said means is movable.

It is more specifically an object of the invention to provide means for swinging said tilting plate about an axis comprising a member secured to said plate and having a head projecting therefrom having a cylindrical portion, a second member movable rectilinearly at right angles to said axis having a portion with a passage extending at right angles therethrough and a block at each side of said head closely embracing the same, said blocks fitting in and being slidably in said passage when said second member is moved rectilinearly to swing said tilting plate, said head having angular movement in said blocks.

These and other objects and advantages of the invention will be fully set forth in the following description made in connection with the accompanying drawings in which like reference characters refer to similar parts throughout the several views and in which:

Fig. 1 is a partial view of certain parts of the invention;

Fig. 2 is a vertical section taken on line 2—2 of Fig. 1 as indicated by the arrows and shown on a reduced scale;

Fig. 3 is a partial view of certain parts of the invention;

Fig. 4 is a vertical section taken on line 4—4 of Fig. 3 as indicated by the arrows shown on an enlarged scale;

Fig. 5 is a vertical section taken on line 5—5 of Fig. 4 as indicated by the arrows also shown on an enlarged scale; and

Fig. 6 is a partial section taken on line 6—6 of Fig. 1 as indicated by the arrows.

Referring to the drawings a portion of a pump of the swash plate type is shown in which it will only be necessary to consider the casing 10 which

is of rectangular shape in vertical cross section, the same having an end plate 10a secured in place by headed and nutted bolts 11 extending longitudinally of said frame. Said frame has 5 at the sides thereof secured by suitable bolts 12 driven bearings 13. Journalled in bearings 13 are the trunnions 14a of a tilting plate 14, said plate being oscillatable about trunnions 14a. The driving shaft 15 of the pump is shown in section 10 in Fig. 2.

Secured to the rear of plate 14 at one side of shaft 15 is a bracket 16. While this bracket could be variously made, in the embodiment of the invention illustrated it is shown as having a flange 16a of general rectangular form with reentrant recesses at opposite ends thereof, said flange being received in a recess 16b formed in plate 14. The bottom of flange 16a engages the plate 14 and is secured in place by a plurality of headed 20 screws 17. Bracket 16 also has a central cylindrical stem 16b which fits in a bore formed in plate 14. Bracket 16 has a head 16c which projects outwardly from flange 16a, said head having semi-cylindrical surfaces 16d at opposite 25 sides thereof. Blocks 18 are formed to fit against the semi-cylindrical surfaces 16d at their inner sides and at their opposite sides said blocks have semi-cylindrical surfaces 18a fitting in a passage 19a formed in a yoke 19b which forms a portion 30 of a member 19. It will be seen that passage 19a is of general elliptical or oblong form having semi-cylindrical ends and that the flat sides of head 16c are spaced slightly from the sides of said passage. Head 16c is shown as having a 35 central cylindrical opening 16e therethrough. Member 19 is in the form of a stem or shaft and at one end is threaded to form a screw portion 19c. A nut 20 embraces screw 19c and has a cylindrical portion 20a journaled in spaced ball bearings 21. Ball bearings 21 are supported 40 in frame 10 and in a ring 22 held in place by a cylindrical cap or casing 23 secured to casing 10 by the headed bolts 24. One of said bearings is also supported on a flange 20b of the nut 20. A nut 26 is also threaded on the outer portion 45 of nut 20, the same engaging a collar 27 engaging the casing or race of one of the bearings 21. Nut 26 is provided with a locking means or washer 28. It will be seen that the outer portion of nut 20 is bored to form a cylindrical chamber 50 surrounding the end portion of screw 19c and being rotatable in a stuffing gland 30 which fits in casing 23, the same being held and adjusted by the headed bolts 31. Packing material 32 surrounds said cylindrical portion of nut 20 and

55

is engaged by the gland 30. The outer portion of nut 20 is provided with a threaded stem 20c which will receive some means for turning said nut. The other end of member 19 is formed as a guide 19d having a plurality of ribs or keys thereon fitting in and movable in grooves or keyways in a member 34 fitting in one side of casing 10 and having a flange 34a secured to said casing by the headed screws 35. Member 34 is provided with a cap 36 secured to its end portion by the headed screws 37.

When it is desired to change the position of tilting plate 14 to change the stroke of the pump member 19 will be moved longitudinally. While this member could be variously moved, in the embodiment of the invention illustrated it will be moved by some means engaging the stem 20c and rotating the nut 20. Nut 20 will be easily rotated and this will cause longitudinal movement of screw 19c. It will be seen that member 19 is confined to non-rotative rectilinear movement by the guide head or portion 19d. When member 19 is thus rectilinearly moved the yoke portion 19b thereof will be moved as will the blocks 18. These blocks will exert movement of head 16c and this will result in tilting plate 14 about the axis of trunnions 14a. It will be seen that head 16c can have oscillating or angular movement relatively to the blocks 18. These blocks can also have movement in the passage 19a, thus moving at right angles to the axis of member 19. The angular movement of bracket 16 and its head 16c is thus taken care of by relative movement between said head, blocks 18 and the yoke 19b. The plate can thus be easily moved and easily and quickly moved through small distances.

The present structure is an improvement upon that disclosed and claimed in the co-pending application of John B. Hawley Jr., S. N. 375,742, filed January 24, 1941, on "Hydraulic pump construction." The present structure is very rugged, durable and comprises few parts. The pumps of the type herein involved are used to create heavy pressure. As the cylinder barrel revolves the cylinders and pistons shift from the inlet to the outlet side of the pump or might be said to commutate from the inlet port to the outlet port. This causes a great impact on the pistons, cylinder barrel and other parts which are thus put under great stress and take, so to speak, quite a pounding. This shock or stress is transmitted to the other parts and the adjusting mechanism for the tilting plate also receives said shock and stress or a large part thereof. The more rugged and simple the adjusting mechanism can be therefore, the better it is. The present structure gives all the necessary movements to permit the tilting action of the tilting plate and yet is at the same time very rugged and durable.

From the above description it will be seen that I have provided a very novel, simple and efficient adjusting mechanism for the tilting plate of a swash plate pump. The invention has been worked out from long experience and is a very practical one. The device has been amply demonstrated in actual practice and is being put into commercial production.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. In a pump of the swash plate type having a casing and a tilting plate swingable in said casing about an axis to vary the stroke of the pump, a shaft member mounted for endwise reciprocation at its ends in said casing and extending substantially at right angles to, and being offset from the axis of said tilting plate, means for restraining said shaft against rotation, said shaft having an intermediate yoke disposed adjacent said tilting plate; means for reciprocating said shaft; and means for transmitting reciprocations of said shaft to said plate, for varying the stroke of said pump, comprising a member secured to said plate and having a head projecting into said yoke, the head of said member having a cylindrical external surface whose axis is disposed at right angles to said shaft and parallel to the axis of said tilting plate, a slide element disposed either side of said head and having internal cylindrical surfaces accurately engaging the cylindrical surface of said head, and adapted to coat solely in rocking engagement therewith, said slide elements also having external cylindrical surfaces coating in rocking engagement with internal cylindrical surfaces formed in the ends of said yoke, the axes of said internal and external cylindrical surfaces of said elements being disposed at right angles to each other, and said elements being freely slideable in a direction normal to said shaft, whereby they may undergo a cross-head motion with respect thereto and yet be maintained in rocking engagement with said head.
2. The mechanism defined in claim 1, wherein said means for restraining said shaft against rotation comprises an internally splined sleeve extending into said casing and slidably coaxing with a set of splines provided on said shaft, and means for rigidly securing said sleeve to a wall of said casing.
3. The mechanism defined in claim 1, wherein said means for reciprocating said shaft comprises a cage bolted over an opening in said casing; an apertured member secured between said cage and said wall; a sleeve projecting through said member into said opening and mounted for rotation in thrust bearings located either side of said member; means on said sleeve cooperating with said bearings for precluding endwise movement of said sleeve, said sleeve surrounding one end of said shaft and being threaded connected thereto, said sleeve projecting outwardly through said cage and having means located externally of the latter for imparting rotative adjusting efforts to said sleeve.
